DESIGN FOR A PEDAL CONTROL DEVICE

Ernest C. Caudill, Kansas City, Kans.

Application June 18, 1947, Serial No. 139,781

Term of patent 3½ years

(Cl. D26—13)

To all whom it may concern:

Be it known that I, Ernest C. Caudill, a citizen of the United States, residing at Kansas City, county of Wyandotte, and State of Kansas, have invented a new, original, and ornamental Design for Pedal Control Device, of which the following is a specification, reference being had to the accompanying drawing, forming a part thereof.

In the drawing:

Figure 1 is a perspective view of a pedal control device, showing my new design;

Figure 2 is a side elevation of the same; and

Figure 3 is a view in elevation showing one end of the device.

I claim:

The ornamental design for a pedal control device, substantially as shown.

ERNEST C. CAUDILL.
